UNITED STATES PATENT OFFICE.

THOMAS H. COSTELLO AND ARTHUR H. HALL, OF CHICAGO, ILLINOIS,
ASSIGNORS TO A. H. ANDREWS & CO., OF SAME PLACE.

ADJUSTABLE STOP-HINGE.

SPECIFICATION forming part of Letters Patent No. 269,562, dated December 26, 1882.

Application filed September 17, 1880. (No model.)

To all whom it may concern:

Be it known that we, THOMAS H. COSTELLO and ARTHUR H. HALL, of Chicago, in the county of Cook and State of Illinois, have invented certain new and useful Improvements in Adjustable Stop-Hinges for Desks, &c., of which the following is a specification.

The object of our invention is to provide a hinge for the lids of desks, so constructed that the lid can be automatically supported or locked in one or more positions, as may be desired, as it is raised, and when it has been elevated to a certain point can be returned to its normal position without obstruction.

The invention is intended more especially for school-desks, but can of course be used on various other articles where such an operation is desirable.

In Letters Patent No. 236,782, granted to us January 18, 1881, we have shown and described a hinge like that herein shown; but the claim of such patent is limited, it having been the purpose to more fully protect the invention therein disclosed by the present application, which is a division of the application upon which said patent was granted.

In the accompanying drawings, Figure 1 is a side elevation of the improved hinge. Fig. 2 is an edge view, partly in section. Fig. 3 is a detail view, showing different positions of the parts of the hinge in dotted lines. Fig. 4 is a view of the inner face of the lid-arm or movable part of the hinge; and Fig. 5 is a detached view of the locking-bolt or sliding tumbler.

The stationary part A of the hinge is to be secured to the standard or body of the desk. It is provided with a transverse recess, E, which is dovetailed for the reception of the sliding bolt D, as shown in Fig. 2. This bolt has an elongated slot, d, at its center, through which the bolt or pivotal pin e, that unites the stationary part A and movable or swinging part B of the hinge, passes.

The inner face of the lid-arm or movable part B is provided with two lugs or shoulders, c b, on opposite sides of the central bearing, h, and in a vertical line, or thereabout, when the end B' is in the position shown in Fig. 2—that is, when the two parts of the hinge are parallel.

The locking bolt or tumbler D is formed with an irregular track or depression, D', in which

the lugs on the part B work, as will presently be described, and the wall of which is notched or shouldered at y y', as shown in Fig. 4.

a is a projecting lug, curved, as shown, on the side toward the notches y y'; and t is a rib, against which the lugs b c strike.

When the parts of the hinge have been assembled, as shown in Fig. 2, the lug b on the part B will rest against the left of the rib t, Fig. 5, and the lug c will be in the upper part of the track D' in the locking-bolt. This is the normal position of the hinge when the lid is down. When the lid-arm B is raised, as shown in Fig. 1, the lug b will strike against the curved or sloping side of the projection a and move the tumbler so far to the right that the shoulder y will be immediately under the lug b. Now, if the motion of the lid is reversed, so as to let the part B down, the lug b will strike the shoulder y and automatically lock the lid in position; and so, in like manner, if the part B is again raised, the tumbler will be driven still farther to the right by the lug b, and the second shoulder, y', will be brought under it and lock the lid in another position. When the lid is raised to a given point, however, the lug c will strike the rib or projection t and drive the tumbler back to the left, so that upon bringing the lid-arm or part B down the lug b will pass down to the right of the projection a, Fig. 5, to the rib t, and restore the hinge to its normal position. The movements of the sliding tumbler are limited by its elongated slot. But two notches y y' are shown; but obviously any desired number may be used, and the lug a shaped to suit them.

Having fully described our invention, what we claim is—

1. The combination of the stationary part of the hinge, the movable or swinging part, a pivot-pin connecting them, and an automatic locking-bolt mounted between them around and loosely upon the pivot.

2. The combination of the stationary part of a hinge having a recess therein, a locking-bolt moving within said recess, and the pivoted swinging part of the hinge having shoulders thereon, which operate the reciprocating or moving bolt and automatically lock the movable part of the hinge in an elevated position.

3. The combination of the stationary recessed

part of the hinge, a reciprocating locking-bolt moving in the recess, and the shoulders on opposite sides of the bearing of the movable part, which shoulders move the locking-bolt to automatically lock the movable part of the hinge in an elevated position and then restore the said bolt to its normal position.

4. The combination, with the movable or reciprocating bolt mounted in the stationary part of a desk-hinge, of the pivoted lid arm having a stud to move the bolt from a locked to an unlocked position as the arm rises above its operative position.

5. The combination of the stationary part of the hinge having a recess therein, the shoul-

dered locking-bolt moving in said recess, and having an elongated slot or opening therein, the pivoted lid-arm having shoulders which operate the locking-bolt, and the pivot-pin which connects the parts.

6. The combination of a desk-standard, a swinging arm, a pivot-pin connecting the standard and arm, and an automatic locking-bolt mounted between the arm and standard around and loosely upon the pivot. 20

THOS. H. COSTELLO.
ARTHUR H. HALL.
